Specification of Letters Patent.

Patented May 26, 1914.

Application filed February 15, 1913. Serial No. 748,702.

To all whom it may concern:

Be it known that we, WILLIAM CASEY and ISAAC LESSES, both subjects of the King of Great Britain, and residents of Kingston, in the Province of Ontario, Dominion of Canada, have invented a new and Improved Magneto, of which the following is a full, clear, and exact description.

This invention relates to a high-tension magneto characterized by an entirely inclosed structure, whereby exposed wiring is done away with, the mechanism being thereby adapted to be made water-proof.

The preferred form of the invention is further characterized by a structure in which the high-tension conductors are short, thereby lessening the chances of grounds and short circuits, and rendering the separate operation of the structure more uniform.

The structure is further characterized by an arrangement of parts whereby the current is delivered at maximum intensity over a long range, due to the relation of the armature and primary circuit breaker when the parts are adjusted in advance or retard position.

The construction set forth presents numerous advantages which will appear as the detailed description thereof proceeds.

Reference is to be had to the accompanying drawings forming a part of this specification, in which similar characters of reference indicate corresponding parts in all the views, and in which—

Figure 1 is a vertical sectional view of the mechanism; Fig. 2 is a top plan view partly broken to show the underlying structure; Fig. 3 is a sectional view on the line 3—3 of Fig. 1; Fig. 4 is a sectional view on the line 4—4 of Fig. 1; while Fig. 5 is a diagrammatic of the ignition system in which the magneto is used.

The elements making up the mechanism are contained in a casing that is substantially waterproof, and consisting of the upper part 1 having the top 2 of insulating material, and the bottom part 3 having an opening 4 therethrough, the shaft 5 passing through the opening into the interior of the casing. The said lower part 3 is counter-bored adjacent its open end for a suitable depth, whereby a shoulder 6 results on the inner side, and the upper part 1 is provided

with an exterior shoulder 7 whereby the two parts may be held closely together; in order to provide for adjustment, to be later more specifically set forth, the lower portion of the upper part 1 is provided with a recess 8 on its outer side, and the upper portion of the lower part 3 is provided with a set screw 9 passing through a threaded opening therein, the inner end of the screw engaging in the said recess, whereby the parts are revolvably held together. The peripheral portion of the lower part 3 is preferably provided with a shoulder 10 carrying a number of openings 11, the upper part 1 being also provided with a shoulder 12 having a recess 13 containing a plunger 14 and a spring 15, the lower end of the plunger being adapted to be engaged in any one of the said openings 11, said engagement being obtained by reason of the said spring. The lower part 3, or, in fact, either of the parts of the mechanism, is provided with arms 13 having openings therein through which suitable securing means, such as bolts or screws, may be passed in order to maintain the mechanism in position on a suitable support.

Extending upwardly into the interior of the casing and mounted on the said shaft 5, is a permanent magnet 14, preferably of the horseshoe type, carrying iron pole faces 15, the said magnet being provided with an opening 16 extending therethrough into which the shaft extends, the relation of the parts being maintained by means of a transversely extending pin 17. This shaft 5 is provided with a shoulder 18, and beneath the shoulder is a cup 19, between which and a second cup 20 secured to the said casing are a number of balls 21, whereby a substantially frictionless turning is provided. The lower end of the casing is preferably provided with a washer 22 of any suitable material, such as felt, retained in position by means of the threaded cap 23, a structure in the nature of a stuffing box being thereby provided, and tending to prevent the entrance of dust or moisture into the casing. The shaft 5 is extended upwardly beyond the said magnet 14 for a suitable distance, and secured to this extension by means of the pin 24 is a sleeve 25 having shoulders 26 thereon (Fig. 4) which are in effect cams, the particular purpose thereof to be later set forth. The upper end of this

sleeve is channeled as at 27 in order to provide one-half of a raceway containing the balls 28.

Concentrically mounted within the upper part 1 of the casing is a bearing 29, fixed to the upper end of the horseshoe magnet is a substantially circular gear 30, preferably of brass, on the inside of which is a channeled plate 31 which, together with the annular pocket 32 on the said bearing 29, form a raceway for receiving the balls 33, whereby frictionless engagement between the parts is provided. Fixed within the said bearing 29 in the upper part of the casing by reason of the screw-threaded engagement 34 is a sleeve 35 having a shoulder 36 at its lower end; the lower interior portion of this sleeve is threaded as at 37 and receive a substantially circular plate 38 carrying the insulation 39, it being noted that this plate 38 is grounded; extending above the said plate is a standard 40 of insulating material having a passageway 41 extending therethrough, within which the conducting rod 42 is positioned, this rod carrying a plate 43 spaced from the before-mentioned circular plate 38, and with it forming a safety spark gap, the lower end of the rod being fixed in position in any desirable manner, as by means of nuts 44; this standard 40 extends upwardly well toward the top of the casing, being counter-bored as at 45 in order to receive the enlarged upper end 46 of the said conducting rod 42, this enlarged end forming a pocket 47 containing a spring 48, making electrical contact between the said rod and the offset 48 extending downwardly from the center portion of the brass plate 49.

The interior of the sleeve 35 is provided with a number of circular channeled rings 51; positioned above the sleeve 35 and the bearing 29 is a gear 52 having a sleeve 53 thereon which surrounds the said standard 40 and lies in spaced relation thereto, the outside of this sleeve carrying rings which, together with the said channeled rings 51 provide raceways, receiving a number of balls 54, whereby the said circular ring 52 may easily rotate. Extending inwardly through the top part 1 of the casing is a pin 55 on which the bevel gears 56-57 are mounted, the gear 56 meshing with the first mentioned circular gear 30 and the gear 57 meshing with the said second circular gear 52.

Secured to the under side of the top portion 2 of the casing are a number of plates 58 of conducting material such as brass, each of which is provided with a threaded spindle 59 extending upwardly therefrom, each spindle having a nut 60 thereon whereby a binding post construction is provided, the said plates 58 being in spaced relation with each other and being in number equal to the number of cylinders or other devices with

which the ignition system is used. On top of the said second circular gear 52 is a support 61 of insulating material, having a pocket therein into which the plunger 62 is seated, the plunger being preferably provided with an offset 63 extending downwardly therefrom, about which is a helical spring 64, the spring keeping the plunger at all times in contact with the central plate 49 and periodically in contact with the said plates 58, whereby the circuit is closed at determined intervals to the devices connected to the binding posts carried by these several plates. Mounted within the said horseshoe magnet 14, and relatively stationary, is the armature made up of a number of laminations 65 suitably held together by means of pins or rivets 66, the laminations forming a frame on which the primary and secondary windings 67-68 are wound; beneath the laminations is a preferably hard rubber box 69 in which the condenser 70 is carried. The top of the armature is adjacent the said shoulder 36 on the lower portion of the fixed sleeve 35, and the lower portion of the armature is in revoluble relation with the upper end of the shaft 5 by means of the ring 71, which, together with the ring 27 previously mentioned, forms raceways receiving the said balls 28.

Referring particularly to Figs. 1 and 4, it will be noted that the under side of the lower portion of the armature carries a pin 72 on which is pivotally mounted a bell crank 73, one end of which is in engagement with a helical spring 74, the other end of the spring being fixed to a support 75; between the said pin 72 and the point of attachment to the spring 74, and carried by the said bell crank is a roller 76 in engagement with the outside of the sleeve 25 and adapted to be periodically engaged by the said projections 26 thereon, the spring keeping the roller in engagement with the said sleeve. Mounted on the lower portion of the armature structure is a suitable support 77 which is in insulated relation with the said structure, the support carrying an adjustable screw 78 having a platinum point 79 thereon with which the platinum point 80 carried by the said bell crank 73 engages, the points being adapted to be separated at certain intervals. When power is applied to the shaft 5 the horseshoe magnet 14 is revolved about the primary and secondary windings carried on the laminations, the said circular gear 30 turning with the magnet, and the second circular gear 52 also turning by reason of the inter-engagement of the parts because of the gears 56 and 57; as the rotation continues the plunger 62 comes into electrical contact with the succession of plates 58, thereby periodically closing the circuit between the central brass plate 49 and each of the elements connected to the said binding posts.

Referring now to Fig. 6, wherein the different elements making up the ignition system are diagrammatically represented, it will be noted that one end of the primary winding 67 is grounded at 82, one end of the secondary winding 68 being also grounded at 82; the other end of the primary is connected to the said support 77 carrying the platinum point 79, and being in circuit with the condenser 70. The platinum point 80 on the said bell crank lever 73 is grounded as at 84. The other end of the secondary winding is connected to the central brass plate 49 by means of the said offset 48, the spring 47 and the conducting rod 42; for the purpose of describing the manner of operation of the device a number of spark plugs 85 are representative of the cylinders of an engine, one side of each plug being grounded as at 80, the other sides of these plugs being connected to the said separate plates 58 carried by the under side of the insulating top piece 2 of the casing; the plunger is represented as always in contact with the said central plate 49 and coming periodically into contact with the separate plates 58. As the magnet operates the turning of the shaft 5 brings the projections 26 on the side of the sleeve 25 into engagement with the roller 76 on the bell crank 73, thereby periodically making and breaking contact between the platinum points 79—80 and opening and closing the circuit through the primary winding 67, by reason of the said grounds 82—84. It will be remembered that the upper part 1 of the casing was described as being adjustable relatively to the lower part 3, being held in adjusted position by reason of the openings 11 in the shoulder 10 (Fig. 2) into which the spring-pressed plunger 14 was adapted to engage; it being clear then that the relation between the make and break of the circuit breaker and the said primary circuit, and the times at which current is supplied to the several spark plugs, may be varied, thereby permitting advance and retard. The said plates 38 and 43 (Fig. 1), the plate 38 being grounded and the plate 43 being connected to one side of the secondary circuit, provide a safety spark gap in the said secondary circuit.

After a consideration of the description in connection with the drawings, it will be apparent that a mechanism has been described which fulfils the purposes of the invention as set forth in the beginning of the specification, the relative size and location of the parts being merely typical of one embodiment of the invention, it being clear that the inventive idea may be comprehended in structures which may vary in size and appearance, but are representative of such inventive idea.

Having thus described our invention,

what we claim as new and desire to secure by Letters Patent is:

1. A mechanism of the class described, comprising a revoluble permanent magnet of horseshoe form supported at its ends, one of the said supports forming a shaft whereby the magnet may be rotated, the said shaft having its end extending through an opening in the magnet, a core between the sides of the magnet and mounted on the said end of the shaft, the said core having a plurality of independent windings thereon, a distributing device for the induced current, and means actuated by the rotation of the magnet and including a movable contact member for controlling said distributing device whereby the current induced in the windings may be placed in circuit at proper times with independent coöperating devices. 75

2. A mechanism of the class described, comprising a permanent magnet of horseshoe form supported at both ends, a core between the sides of the magnet and having a plurality of windings thereon, one of the supports of the said magnet being a shaft whereby the magnet may be rotated, and means actuated by the turning of the magnet and including a movable contact member whereby the current induced in the windings may be placed in circuit at proper times with independent coöperating devices. 85

3. A mechanism of the class described, comprising a revoluble magnet, and a stationary core carrying windings in which current is induced, said mechanism also comprising a distributing plate and a movable brush, the brush coming into contact with different portions of the said plate whereby different circuits are placed in communication in the said windings. 100

4. A mechanism of the class described, comprising a permanent horseshoe magnet, a revoluble shaft to which the magnet is secured, the shaft having an extension, a core between the sides of the magnet, the lower portion of said core being mounted loosely on the shaft extension, and the core and the magnet being movable relatively one to the other, a plurality of windings on the core, a contact plate in the circuit of one of the windings, a number of contact plates connected to different coöperating devices, a brush in contact with the first-mentioned contact plate and adapted to contact successively with the other contact plates, a circular gear carried at the upper end of the magnet and turning therewith, a second circular gear carrying said brush, and means for driving the gear carrying the brush from the gear carried by the magnet. 110

5. A mechanism of the class described, comprising a current inducing mechanism including a revoluble permanent magnet, a shaft on which the magnet is mounted, the shaft having an upward extension, a core 130

between the sides of the magnet, a plurality of windings on the core, a circuit breaker in one of the circuits of the current inducing mechanism and supported at the lower end of the core, a distributing device including a contact in the other circuit of the current inducing mechanism, a plurality of contacts adapted to be connected to independent devices, a brush for connecting the first contact successively with the other contacts, a driving connection between the said revoluble magnet and the said brush, and a sleeve secured on the upward extension of said shaft and having cams thereon for operating said circuit breaker, the said core being mounted at its lower end on the upper end of said sleeve.

6. A mechanism of the class described, comprising a revoluble magnet for maintaining an electric field, windings within the field whereby current is induced, a circuit breaker in the circuit of one of the windings, a distributing plate having a plurality of members one of which is in the circuit of the other winding, a movable contact member in contact with the said member in the circuit of the winding and adapted to come into contact with the other members of said distributing plate whereby different co-operating elements may be brought into the said circuit, and means for bringing the distributing plate into different positions relatively to the circuit breaking device, whereby the timing of the several co-operating elements may be varied.

7. A magneto electric current generator, comprising a casing consisting of an upper and a lower member, the upper member being mounted to turn relative to the lower member, co-operating current inducing elements, a distributing plate secured to the top portion of the upper member of the casing at the under side thereof and comprising a central contact and a number of contacts arranged around the central contact and connected to different circuits, a brush engaging the central contact and successively engaging the other contacts, means whereby the brush and the revoluble element of the current inducing mechanism turn together, the upper member of the casing being provided at its lower part with a recess in its outer face, and a set screw carried by the lower member of the casing at its upper part and engaging said recess, whereby the members of the casing are revolubly held together and the upper member can be adjusted to cause the distributing plate to occupy different positions in order that the times of engagement of the brush with the said contacts may be varied, the peripheral portion of the lower member being provided with a shoulder having a series of openings, the upper member of the casing also having a shoulder provided with

a recess, and a spring controlled plunger in said recess adapted to engage either of said openings to hold the upper member in the adjusted position.

8. A magneto electric current generator, comprising a revoluble horseshoe magnet maintaining a permanent electric field, and a core between the sides of the said magnet, the core carrying a plurality of windings, the core and windings being movable independently of the said magnet and relatively thereto.

9. A magneto electric current generator, comprising a permanent magnet of horseshoe form maintaining a permanent electric field, a shaft on which the magnet is mounted, the shaft having an upward extension, a core between the sides of the magnet, the lower portion of the core being in revoluble relation with the upper end of said shaft extension, the said core having a plurality of windings, a circuit breaker in one of the windings, and supported at the lower end of the core, the said winding being also in circuit with a condenser, and means secured to the said shaft extension for operating the circuit breaker, the core within the windings thereon being movable relatively to the said magnet, whereby current is induced in the said circuit breaker being actuated when the said relative movement takes place.

10. In a magneto electric current generator, the combination of a horseshoe magnet revolvably mounted in position, a circular gear carried by the magnet and turning therewith, a second circular gear carrying a plunger adapted to contact with the several parts of a distributing plate, and intermediate gears between the said circular gears, whereby the turning of the magnet is imparted to the said plunger.

11. In a magneto electric machine, a casing made up of two parts relatively one to the other, a horseshoe magnet for maintaining a permanent field revolvably mounted in one of the parts, a distributing plate carried by the other part, a core between the sides of the magnet carrying a plurality of windings, means actuated through turning of the magnet for bringing the several parts of the distributing plate into circuit with one of the windings, and means for maintaining the parts of the casing in such position relatively one to the other that the times at which the portions of the distributing plate are placed in circuit with the said winding may be varied.

12. In a magneto electric machine, a revoluble permanent magnet, a core adjacent the magnet having primary and secondary windings thereon, means for revolving said magnet, a gear carried by said magnet and turning therewith, a second gear, a spring-controlled contact member carried by said second gear, a driving connection between the

said gears, a distributing plate having a central member connected with the secondary winding, and a plurality of separate members, the said spring-controlled contact member being always in contact with the said central member of the distributing plate and adapted to connect the same successively with the other members of said plate.

13. In a magneto electric machine, a casing comprising two members, a permanent magnet revolvably mounted in one of said members, a distributing plate carried by the other member of the casing, a core adjacent the magnet and having primary and secondary windings thereon, the said distributing plate having a central member in the circuit of the secondary winding, and members surrounding the central member and insulated therefrom and from each other, a spring pressed contact member held in contact with the central member of the distributing plate and adapted to contact with the other members of said plate, and means actuated by the turning of the magnet for moving the spring pressed member into engagement with the plate surrounding the central plate, to bring the said plates successively into circuit with the said secondary winding, the member of the casing carrying the distributing plate being adjustable relatively to the other member of the casing, and means for holding the said member in adjusted position.

14. In a magneto electric machine, a revoluble permanent magnet, a core adjacent the magnet having primary and secondary windings thereon, means for revolving said magnet, a distributing plate having a central contact member and a plurality of separate contact members, the contact members being insulated from each other, the central contact member having a downwardly extending portion, a conducting rod connected with the secondary winding and having an enlarged upper end forming a pocket, a spring in said pocket making electrical contact between the conducting rod and the downwardly extending portion of the cen-

tral contact member, a spring controlled contact member, and means for driving said contact member from said revoluble magnet, the said spring controlled contact member being in contact with said central member of the distributing plate and adapted to connect the same successively with the other members of said plate.

15. In a magneto electric machine, a casing comprising an upper and a lower member, a revoluble shaft extending into the lower member of the casing, a permanent magnet within said member of the casing and carried by said shaft, a distributing plate carried at the upper portion of the upper member of the casing, a core between the sides of the magnet and carrying a plurality of windings, means actuated by the turning of the magnet for bringing the several parts of the distributing plate into circuit with one of the windings, a circuit breaker in the circuit of the other winding and actuated from the shaft of said magnet, one of the members of the casing being mounted to turn relatively to the other member, whereby the distributing plate may be brought into different positions relatively to the circuit breaking device and the times at which current is supplied to the different portions of said distributing plate may be varied, and means for holding the said movable member of the casing in the adjusted position.
